DESIGN FOR A BEER BOTTLE

Clarence R. Deible, Marienville, Pa., assignor to Knox Glass Associates, Inc., Oil City, Pa., a corporation of Pennsylvania

Application September 13, 1938, Serial No. 79,868

Term of patent 14 years

To all whom it may concern:

Be it known that I, Clarence R. Deible, a citizen of the United States of America, residing at Marienville, in the county of Forest and State of Pennsylvania, have invented a new, original, and ornamental Design for Beer Bottles, of which the following is a specification, reference being had to the accompanying drawing, forming part thereof.

In said drawing:
Fig. 1 is a top plan view of a beer bottle showing my new design; and

Fig. 2 is a front elevation.

I claim:

The ornamental design for a beer bottle, as shown.

CLARENCE R. DEIBLE.
